UNITED STATES PATENT OFFICE.

JAMES C. DAWSON, OF ST. LOUIS, MISSOURI, ASSIGNOR TO SIEBER & TRUSSELL MANUFACTURING COMPANY, A CORPORATION OF ILLINOIS.

LOCK.

No. 850,877.

Specification of Letters Patent.

Patented April 16, 1907.

Original application filed April 30, 1906, Serial No. 314,435. Divided and this application filed November 15, 1906. Serial No. 343,609.

To all whom it may concern:

Be it known that I, JAMES C. DAWSON, a resident of the city of St. Louis, State of Missouri, and a citizen of the United States, have 5 invented certain new and useful Improvements in Locks, of which the following is a specification, and which are illustrated in the accompanying drawings, forming a part thereof.

10 This invention has been divided from my copending application for patent on looseleaf binders, Serial No. 314,435, filed April 30, 1906.

15 It relates to locks having an oscillatable bolt and a tumbler for securing the bolt in its advanced position, and has for its object to provide a lock particularly adapted for use in situations in which a portion of the bolt is necessarily exposed when the lock is closed.

20 A detail of the invention provides for a cam engagement between a tumbler of the lock and the bolt when the latter occupies an intermediate position to effect the withdrawal of the bolt.

25 In the accompanying drawings, Figure 1 is an end elevation of a lock constructed according to the invention and shows a detail of the sheet-holding mechanism of a looseleaf ledger to which the lock may be applied. 30 Fig. 2 is a longitudinal section on the line 2 2 of Fig. 1. Figs. 3 and 4 are plan views showing the mechanism of the lock in different positions. Fig. 5 shows a tumbler used in the lock, and Fig. 6 is a detail view of a key used 35 for opening the lock.

The particular form of lock illustrated in the drawings may be employed for preventing the unwarrantable opening of the binder mechanism of a looseleaf ledger having relatively movable clamping-plates for gripping the sheets to be bound. As shown, the binder mechanism comprises an intermediate back member 12, upon which the clamping members, as 10 11, are slidably mounted, 40 and each of these members carries a plurality of telescoping binding-post members 13.

The movement of the clamping members 10 and 11 to open and close the binder is effected by means of cam-levers 14 15, pivotally mounted on the back member 12 and operatively engaged by a cross-head 16, carried by a threaded rod 17. One end of the threaded rod 17 registers with an opening 18 in the end flange 19 of the back member 12,

and through this opening a key or crank-rod 55 (not shown) may be inserted to turn the threaded rod 17.

The lock forming the subject of the invention is shown applied to the frame of the binder to provide means for closing the opening 18. It preferably comprises a chambered casing 20, which, as shown, has a laterally-extending flange 21 for receiving attaching-screws 22 23, entering the back member 12 of the binder. A reciprocable bolt 24 extends 60 through the casing 20 and, as shown, is provided upon one of its ends with a thumb-piece 25 for the application of pressure to close the lock. Preferably, as most clearly shown in Fig. 2, the thumb-piece 25 occupies 70 a position flush with the wall of the casing 20 when the lock is closed.

The bolt 24 is provided with one or more lugs adapted to be engaged by the lock-tumblers. Two such lugs 26 27 are shown, and 75 these take the form of lateral wings, each having a forwardly-inclined face 28 and an abrupt shoulder 29. A tumbler, as 30 31, moves across the path of each of the wings 26 27 and is most conveniently fixed against lateral displacement by means of pins 32, mounted in the wall of the lock-casing and engaging slots 33, formed in the tumbler. Each of the tumblers is provided with a shoulder, as 34 35, for engaging a lug or wing of the bolt 80 and with a flange, as indicated at 36 37, adapted to be engaged by the wards of a key, the flange 36 of the tumbler 30 preferably extending across the face of the bolt 24 to a position adjacent the key-opening 38 in the 85 front wall of the casing 20. Preferably the tumblers of the lock are spring-advanced, and in the form of construction illustrated a retractile spring 39, reacting between the two tumblers, is provided for this purpose. 90

In use the flange 21 of the lock-casing may be covered by the leaves of the ledger secured between the clamping-plates 10 11, thereby preventing access to the screws 22 23 to remove the lock from the binder-frame. The bolt 24 is advanced to close the opening 18 by pressure on the thumb-piece 25, and when in this position it is firmly secured against withdrawal by the engagement between the shoulders 34 35 of the tumblers 30 31 and the abrupt faces of the lugs 26 27 of the bolt. To open the lock, a key 40 is inserted through the aperture 38 in the wall of the lock-casing, 95 100 105

and when turned its wards engage the flanges 36 37 of the tumblers to retract them, and one of them contacts with a portion of the bolt, as the inclined face of the wing 27, to raise it. When the key has been given a partial rotation, the tumblers 30 31 are released and are advanced by the spring 39 upon the inclined faces 28 of the wings 26 and 27, respectively, engaging them by a cam action to complete the raising of the bolt. This action is facilitated by providing one of the tumblers, as 31, with an inclined forward face 41. When the bolt 24 is advanced in closing the lock, the tumblers 30 31 are displaced to allow the wings of the bolt to pass by a similar cam action.

The number of tumblers in the lock and the configuration of the wards of the key 40 may be varied at will to increase the difficulty 20 of picking the lock or to provide a series of locks for each of which a different key is required.

I claim as my invention—

1. In a lock, in combination, a pressure-advanced bolt having a lug, a spring-advanced tumbler movable across the path of the lug on the bolt, the rear face of the tumbler being inclined and the forward face of the tumbler being abrupt, and a key for withdrawing the tumbler and partially withdrawing the bolt.

2. In a lock, in combination, a pressure-advanced bolt having a lug, a spring-advanced tumbler movable across the path of the lug on the bolt, the rear face of the tumbler being inclined and the forward face of the tumbler being abrupt, and a key for withdrawing the tumbler and partially withdrawing the bolt.

bler and the forward face of the bolt-lug being inclined and the forward face of the tumbler and the rear face of the bolt-lug being abrupt, and a key for withdrawing the tumbler and partially withdrawing the bolt.

40

3. In a lock, in combination, a pressure-advanced bolt having a lateral wing, one face of the wing being inclined and the opposite face of the wing being abrupt, a spring-advanced tumbler engaging the wing, and a key 45 engaging the tumbler to move it away from the bolt and engaging the bolt to withdraw it.

4. In a lock, in combination, a casing, a reciprocable bolt extending through the casing and having lateral wings with abrupt and 50 oblique shoulders, a pair of spring-advanced tumblers engaging such shoulders, and a key for withdrawing the tumblers and partially withdrawing the bolt.

5. In a lock, in combination, a chambered 55 casing, a reciprocable bolt extending through the casing and having lateral wings each having one abrupt shoulder and one inclined face, a pair of reciprocative tumblers, one engaging each wing, a retractile spring reacting between the tumblers to hold them in engagement with the bolt, and a two-ward key 60 engaging the tumblers to move them away from the bolt and engaging a wing of the bolt to raise it.

JAMES C. DAWSON.
